UNITED STATES PATENT OFFICE.

AROORD LEE GOULD, OF LONG BEACH, CALIFORNIA.

DESIGN FOR A TOY DOG.

Application filed October 22, 1925. Serial No. 15,219. Term of patent 3½ years.

To all whom it may concern:

Be it known that I, AROORD L. GOULD, a citizen of the United States, residing at Long Beach, in the county of Los Angeles and State of California, have invented a new, original, and ornamental Design for a Toy Dog, of which the following is a specification, reference being had to the accompanying drawing, forming part hereof.

In the drawing:

I claim:

The ornamental design for a toy dog, as shown.

AROORD LEE GOULD.
